UNITED STATES PATENT OFFICE.

JAMES M. McCLELLAN, OF EVERETT, MASSACHUSETTS.

BOILER AND FIRE-BOX CONSTRUCTION.

1,203,376.

Specification of Letters Patent. Patented Oct. 31, 1916.

Application filed March 13, 1913. Serial No. 753,944.

To all whom it may concern:

Be it known that I, JAMES M. McCLELLAN, a citizen of the United States, and resident of Everett, in the county of Middlesex and 5 Commonwealth of Massachusetts, have invented an Improvement in Boiler and Fire-Box Constructions, of which the following description, in connection with the accompanying drawings, is a specification, like 10 characters on the drawings representing like parts.

This invention relates to boilers and fire-boxes, and more particularly to constructions of the locomotive type.

15 The character of the invention may be best understood by reference to the following description of an illustrative embodiment thereof shown in the accompanying drawing, wherein:

20 Figure 1 is a vertical longitudinal section through a portion of an illustrative barrel and fire-box embodying the invention; Fig. 2 is a vertical transverse section taken on line 2—2 of Fig. 1; Fig. 3 is a section taken on line 3—3 of Fig. 1; Fig. 4 is a vertical transverse section of a modification; Fig. 5 is a sectional detail taken on line 5—5 of Fig. 4; and Figs. 6, 7 and 8 are 25 details to be referred to.

30 Referring to the drawing, the illustrative structure shown therein as embodying the invention comprises a barrel 1 containing usual flues 3 having ends entering a flue-sheet 5 connected with said barrel by a 35 throat sheet 7. The meeting ends of the flue-sheet and throat sheet are connected by a strip 11 secured thereto. Interposed between the lower ends of said sheets is a foundation member 9 secured thereto.

40 An important feature of the invention relates to the fire-box closure. This closure comprises a series of hollow sections or tubes 15 of substantial diameter having ends entered into said flue-sheet, said tubes being 45 inclined downward from said sheet toward the rear end of the fire-box where they are entered into and communicate with a hollow rear wall comprising spaced plates 17 (Fig. 1) flanged and riveted together. As shown, 50 these inclined tubes have their ends bent somewhat in order that they may enter the flue-sheet and inner wall 17 perpendicularly thereto. The series of tubes described are assembled in arch or other appropriate form

and constitute the sides and crown of the 55 fire-box as well shown in Fig. 2.

Preferably the tubes do not contact with one another, but are slightly spaced and are connected by fillers 19 which may be welded to the tubes by the well known oxy-acetylene process, so that in effect the 60 assembly of tubes constitutes an integral whole. As shown herein, the fillers do not connect the tubes on a line passing through and common to their diameters, but are offset somewhat toward the exterior of the fire-box. This is a very advantageous arrangement since, among other things, it enables 65 a tube portion greater than an arc of 180 degrees to be exposed to the high heat 70 within the fire-box and thereby greatly increases the capacity of the tube as a steam generating element.

The top of the rear wall is a substantial 75 distance beneath the top of the barrel and the wall tubes have a decided inclination toward said wall. This inclination is an important feature of the invention and one great advantage thereof resides in the fact that a substantial lowering of the water 80 level in the barrel uncovers but a very small portion of the tubular fire-box closure which is in communication with said barrel. In other words, the water in the barrel may lower to a level beneath any usual or probable 85 level without lowering the water in the fire-box inclined tubes sufficiently to dangerously expose the latter.

As shown herein, the uppermost portions 90 of the tubes are above the barrel water level, but the flow of wet steam therethrough will take up heat from said tube portions and prevent their burning out. As shown herein, the series of inclined tubes do not extend to the bottom of the sides of the fire-box, 95 but the lower portions of the sides are formed by U-shaped plates 21 each having a foundation member 23 interposed between the walls of the chamber formed by said plates and riveted or otherwise secured thereto. Said walls may be stiffened by stay bolts appropriately distributed. Each U-shaped plate extends to and through an aperture 25 in the lower portion of the flue-sheet and is riveted to a flange 21^a projecting from said flue-sheet around said aperture. The opposite end of each U-shaped plate extends to the inner sheet 17 of 100 105

the rear wall and is riveted or otherwise secured to a flange 26 projecting from an aperture in said sheet into said chamber. The U-shaped chamber converges vertically from the flue-sheet toward the rear wall. To permit an ample circulation through this chamber and compensate for this narrowing thereof, its end adjacent the rear wall may be flared horizontally as at 21^b (Fig. 3). Thus the chamber will be of sufficient transverse section throughout to provide a large free circulation of water from the barrel to the hollow rear wall.

Heretofore it has been customary to incline the grate of the fire-box toward the front of the latter in order that the draft up through the grate might burn the fuel more uniformly over the grate and convey the products of combustion as directly to the barrel flues as possible. The value of hollow walls of a fire-box for generating steam makes it desirable to direct the products of combustion back so they sweep around in heating contact with as much of the interior surface of the fire-box as possible. To accomplish this a baffle was introduced in the fire-box, but the grate was permitted to remain with its forward inclination. This arrangement of grate and baffle unduly confines and restricts the free and uniform burning of the products of combustion since it is obvious that to take advantage of the full grate area there should be a draft through the grate substantially perpendicular to the plane of the grate. In order to approach this latter condition as much as possible, instead of inclining the grate toward the front of the fire-box as has heretofore been the practice, there is provided a grate 27 which inclines toward the rear of the fire-box. This grate is provided with a baffle 31 of tiles supported by tubes 33 inclined and slightly arched, the ends of said tubes being entered into the flue sheet and inner sheet of the rear wall. The water may circulate through said tubes and prevent their burning out. By this widely diverging arrangement of grate and baffle the products of combustion from substantially the entire grate area are directed rearwardly to sweep around and contact with the rear portions of the tubes in the fire-box, thereby greatly increasing their effectiveness in heating all of the steam generating surfaces within the fire-box. To facilitate the introduction and removal of these baffle supporting tubes the throat sheet and outer sheet of the rear wall are provided with plugs 35 entered into holes in said sheets opposite the ends of said tubes.

To prevent ashes from entering between the portions of tubes adjacent the grate bars, fillers 37 (Fig. 1) may be interposed between said tubes and welded thereto. To provide additional steam generating surfaces, a se-

ries of large supplemental tubes 39 similar to the fire-box closure tubes 15 may be provided. These tubes may be introduced within the fire-box adjacent the crown thereof, and as shown herein, are arranged in a horizontal row with ends entered and expanded in the flue-sheet and inner sheet of the rear wall and inclined from the former down toward the latter. Preferably the inclination and diameters of the supplemental tubes are greater than those of the wall closure tubes since, being located in the hottest part of the fire-box, they are more active in generating steam and require more water. The ebullition or steam generating process occurring in these tubes tends to create rapid upward currents in them. The greater inclination of these tubes offers less opposition to the upward flow of these rapid currents. The location of the supplemental tubes beneath the crown shields the latter somewhat from the hot products of combustion in the fire-box, and thereby protects the crown and prevents liability of its being burnt out. To facilitate removal and replacement of any of the wall and supplemental steam generating tubes, the outer sheet of the rear wall may be provided with hand holes, each somewhat larger than the diameter of the tube opposite thereto and having a closure plug 43.

The fire-box may be provided with a superheater shown herein as a series of relatively small U-shaped return tubes 45 having ends entered through the flue-sheet 5 and preferably located between the supplemental steam generating tubes 39 and the crown tubes of the fire-box. To contribute to the support of the superheater tubes they may rest on transverse bridge bars 47 interposed between the tubes at intervals.

As stated, the water is fed from the barrel through the U-shaped chambers at the bottoms of the sides of the fire-box to the rear wall of the latter. The water rises in this wall and circulates up through the inclined closure tube and supplemental tubes, the steam generated by said tubes being directly delivered into the upper portion of the barrel. To conduct the steam into the superheater there may be provided a receiving or entrance chamber 49 (Figs. 1 and 8) comprising a wall plate 51 conveniently of channel shaped section having a flange riveted or otherwise secured to the flue sheet 5 referred to. This plate 51 is shaped to conform to the outline formed by the assembly of superheater tubes as shown in dotted lines in Fig. 2. The wall of the chamber 49 opposite the flue sheet 5 is formed by a plate 53 conveniently integral with and formed of the same casting as the wall 51.

Each of the U-shaped superheater tubes comprises two legs, one longer than the other. The short leg is entered through the flue sheet 5 and communicates with the in-

terior of the chamber 49, while the long leg projects through the flue sheet and chamber and through the plate 53. To take steam from as high a portion of the barrel as possible, the chamber 49 may be provided with a series of upright inlet tubes 55 having ends expanded or otherwise secured in the upper wall of said chamber. The steam passes from the upper portion of the barrel through 10 said inlet tubes 55 into the receiving chamber 49 passing thence through the short legs of the U-shaped superheater tubes and returning through the long legs of the latter. To receive and conduct the steam from said 15 long legs of the superheater tubes there may be provided a chamber 57 preferably provided with a double wall to insulate and prevent the loss of temperature in the chamber from the lower temperature of the surrounding steam in the barrel. This double wall may terminate in end flanges 59 and 61, one being secured to the flanges of the receiving chamber wall 51 and the other being secured to a double wall pipe 63 for conducting the 20 superheated steam through the barrel. To permit access to the shorter legs of the U-shaped superheater tubes the entrance chamber plate 53 may be provided with plugs 65 threaded in apertures in said plate opposite 25 the ends of the short legs of the superheater tubes.

In Figs. 4 and 5 is shown a rear wall construction comprising spaced plates 67 flanged and riveted together, said plates being similar in form to the plates 17, 17 shown in Fig. 35 1 of the drawing, with the exception that instead of a foundation member such as shown in Figs. 1 and 3 extending straight across the fire-box from side to side of the latter there is provided a short foundation member 69 interposed between the plates 67 and extending a substantial distance across the fire-box toward the opposite sides of the latter, the plates 67 being cut away to provide a 40 substantial space in the wall beneath the door of the fire-box to receive the running gear frame of the locomotive and permit an advantageous lowering of the fire-box.

As shown in Fig. 1, the wall closure tubes and supplemental tubes have ends expanded 50 into apertures in a flat flue sheet. In some cases it may be desirable to form or press nipples 71 (Fig. 6) from said sheet. Each of these nipples has an inturned flanged 55 aperture 73 into which the end of a tube may be expanded or welded. If desired, the inturned flange may be omitted in some cases and straight tubular nipples such as 75 (Fig. 7) may be pressed or formed from the flue sheet and the tubes may be introduced and welded therein. By the construction shown in Figs. 6 and 7 it is not necessary to bend the ends of the tubes as shown in Fig. 1, but on the contrary they may remain 60 straight throughout.

The fire-box closure described is extremely simple and strong in construction, with no stay bolts, rivets or objectionable projections to invite sediment or incrustation, but the tubes thereof are smooth throughout and thereby permit a free unimpaired circulation 70 therethrough. The offset fillers connecting the tubes leave substantial portions of the latter exposed to the high heat within the fire-box and thereby very materially increase 75 the available steam generating surface of the fire-box. Also because such a large portion of a tube is exposed to the direct heat in the fire-box the tendency is to heat the tube throughout to the same temperature. The 80 high temperature of the principal portion of the tube is readily conducted to the smaller portion of the tube outside of the filler and thereby raises the temperature of the latter. The fact that the inner faces of 85 the filler are exposed to the direct heat of the fire-box also assists in maintaining this uniform temperature. The offset location of the fillers has a further important advantage since it permits the spacing of the tubes 90 sufficiently to allow a free expansion and contraction thereof without crowding one another and distortion of the assembly of tubes as a whole.

In practice, the water level in the barrel 95 of the boiler should never be permitted to be lowered beneath the top flues in the barrel. Because of the inclination of the fire-box closure and supplemental steam generating tubes there remains but a very small portion of these tubes above the water level of said top flues. As a result, there can be no possibility of the water level being lowered sufficiently in said wall closure and supplemental steam generating tubes sufficiently 100 to cause their being burnt and ruptured. The liability of rupture of a wall closure tube is small, but if under long usage or neglect a tube should be burnt out or ruptured, being but a small unit part of the 105 wall, no serious explosion would result therefrom.

It will be understood that the invention is not limited to the particular construction shown, but that various modifications may 115 be made therein without departing from the spirit and scope of the invention. It is not indispensable that all of the features described should be used conjointly since some of them may be used separately to advantage. 120

What I claim as new and desire to secure by Letters Patent is:

1. In a fire-box, a side wall comprising a series of large circulation tubes inclined downward from one end of the fire-box toward the other and extending longitudinally of the latter, said tubes being welded together intermediate their ends to form in effect a continuous integral side closure. 125
2. In a fire-box, a side wall comprising 130

- a series of hollow circulation sections inclined downward from one end of the fire-box toward the other, and means intermediate the ends of said sections for securing them together, thereby providing a continuous side closure for the fire-box.
3. In a fire-box, the combination of a flue sheet and a side wall comprising a series of circulation tubes connected to said sheet and inclined downward away therefrom, and means intermediate the ends of said tubes for securing them together, thereby providing a continuous side closure for the fire-box.
10. In a fire-box, the combination of a side wall comprising a series of circulation tubes inclined downward away from the flue sheet of the fire-box, means intermediate the ends of said tubes for securing them together, return tubes inclined downward away from said flue sheet, and steam generating tubes extending downward away from said flue sheet beneath said return tubes to protect the latter from the fire in the fire-box.
15. In a fire-box, the combination of a flue sheet at one end thereof, a hollow wall at the opposite end thereof, and side walls connecting said flue sheet and end wall, each comprising a series of large circulation tubes inclined downward from said flue sheet to said end wall, and means intermediate the ends of said tubes for securing them together, thereby providing a continuous side closure.
20. In a fire-box, a side wall comprising a series of large tubes inclined downward from one end of the fire-box toward the other, fillers interposed between and welded to said tubes and offset from the centers thereof to provide steam generating surfaces adjacent the interior of the fire-box each of an arc greater than 180 degrees.
25. In a fire-box, the combination of a crown and side walls composed of series of circulation tubes inclined downward from one end of the fire-box toward the other, and means intermediate the ends of said tubes for securing them together to form a continuous side and crown closure for the fire-box.
30. In a fire-box, the combination of a crown and side walls composed of series of circulation tubes inclined downward from one end of the fire-box toward the other, and means intermediate the ends of said tubes for securing them together to form a continuous side and crown closure for the fire-box.
35. In a fire-box, the combination of an arched crown and side walls composed of a series of tubes inclined downward from one end of the fire-box toward the other, and means intermediate the ends of said tubes for securing them together to form a continuous side and crown closure.
40. In a fire-box comprising a flue sheet, a hollow end wall, side walls and a crown connecting said flue sheet with said end wall comprising a series of closely arranged tubes inclined downward from said flue sheet to said hollow wall, and means intermediate the ends of said tubes for securing them together.
45. In a fire-box, the combination of a flue sheet, a hollow rear wall offset downward from said flue sheet, and side walls connecting said flue sheet with said hollow wall comprising series of circulation tubes inclined downward from said flue sheet to said end wall, and means intermediate the ends of said tubes for securing them together, thereby providing continuous side closures.
50. In a fire-box, the combination of a flue sheet, a hollow rear wall offset downward from said flue sheet, and side walls connecting said flue sheet with said hollow wall comprising series of circulation tubes inclined downward from said flue sheet to said end wall, and means intermediate the ends of said tubes for securing them together, thereby providing a continuous side closure for the fire-box.
55. In a fire-box, the combination of a flue sheet, a hollow rear wall offset downward from said flue sheet, and side walls connecting said flue sheet with said hollow wall comprising series of circulation tubes inclined downward from said flue sheet to said end wall, and means intermediate the ends of said tubes for securing them together, thereby providing a continuous side closure for the fire-box.
60. In a fire-box, the combination of a flue sheet, a hollow rear wall offset downward from said flue sheet, and side walls connecting said flue sheet with said hollow wall comprising series of circulation tubes inclined downward from said flue sheet to said end wall, and means intermediate the ends of said tubes for securing them together, thereby providing a continuous side closure for the fire-box.
65. In a fire-box, the combination of a flue sheet, a hollow rear wall offset downward from said flue sheet, and side walls connecting said flue sheet with said hollow wall comprising series of circulation tubes inclined downward from said flue sheet to said end wall, and means intermediate the ends of said tubes for securing them together, thereby providing a continuous side closure for the fire-box.
70. In a fire-box, the combination of a crown and side walls comprising series of circulation tubes inclined downward away from the flue sheet of the fire-box, and sets of steam generating tubes inclined downward away from the flue sheet one of said sets being located beneath the other to protect the same from the fire in the fire-box.
75. In an apparatus of the class described, the combination of a barrel with a fire-box, a flue sheet between them, flues in said barrel connected to said sheet, side wall closure tubes communicating with said barrel through said sheet and inclined downward away from the latter, and means connecting said tubes intermediate their ends, thereby providing a continuous side closure for the fire-box.
80. In an apparatus of the class described, the combination of a barrel having flues therein, a flue sheet connected to said barrel, and a fire-box comprising a hollow end wall, a hollow steam generating external closure for the fire-box comprising tubes connected to said flue sheet and end wall and inclined downward from the former to the latter, means for securing said tubes together intermediate the ends thereof; superheater tubes adjacent the top of the fire-box and inclined downward from said flue sheet, and supplemental steam generating tubes distributed across the fire-box adjacent said superheater tubes and inclined downward from said flue sheet to said end wall.
85. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
90. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
95. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
100. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
105. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
110. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
115. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
120. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
125. In an apparatus of the class described, the combination of a barrel; flues therein; a flue-sheet; a hollow rear wall; a steam generating side closure wall for said fire-box comprising a series of hollow sections communicating with said barrel and wall and inclined from said flue-sheet toward said rear wall, whereby the lowering of the water level in the barrel uncovers a portion of said wall gradually increasing laterally.
130. In a fire-box, the combination of a

- flue sheet a wall comprising a series of superposed, hollow sections inclined downward away from said flue sheet; a baffle extending transversely to said sections; and a 5 grate beneath said baffle inclined toward the rear end of the fire-box.
17. In a fire-box, the combination of a wall comprising a series of hollow sections inclined toward the rear of the fire-box; and 10 a water-circulation chamber located beneath said sections.
18. The combination of a wall comprising a series of hollow sections inclined toward the rear of the fire-box; and a water circulation chamber located beneath said sections 15 and having walls stayed together.
19. In a fire-box, the combination of a wall comprising a series of hollow sections inclined toward the rear of the fire-box; and 20 a circulation chamber beneath said sections and flaring in different directions toward its ends.
20. In a fire-box, the combination of a wall comprising a series of hollow sections 25 inclined toward the rear of the fire-box; and a chamber beneath said sections comprising a U-shaped plate having stayed surfaces.
21. In an apparatus of the class described, the combination of a barrel with a flue-sheet, 30 and a throat sheet; flues for said barrel; a hollow rear wall; a series of hollow sections inclined downward from said flue-sheet toward said rear wall; and a water circulation chamber beneath said sections for conducting water from said barrel to said rear wall.
22. The combination of a barrel with a flue-sheet; a hollow rear wall; a series of hollow wall sections inclined from said flue- 35 sheet toward said rear wall; a U-shaped plate beneath said tubes; and a foundation member interposed between the lower ends of said plate.
23. In a fire-box, the combination of a flue-sheet, a back wall, and crown and side 45 tubes directly connected with said sheet and wall.
24. In a fire-box, the combination of a flue-sheet with flues projecting in one direction therefrom and wall closure tubes projecting in an opposite direction therefrom. 50
25. In a fire-box, the combination of a series of hollow wall sections having provision providing circulation toward one end of the fire-box and thence toward the opposite end thereof. 55
26. In a fire-box, the combination of a barrel, a flue sheet, and hollow wall sections having provision for receiving a downward circulation from the lower part of the barrel 60 through the flue-sheet, and provision permitting an upward circulation to the upper part of said barrel.
27. In a fire-box, the combination of a barrel, a flue-sheet, and hollow wall sections 65 for the fire-box projecting substantially longitudinally of said barrel.
28. In a fire-box, the combination of a closure comprising sides and a crown of hollow inclined water circulation sections. 70
29. In a fire-box, the combination of a closure comprising sides and a crown of hollow inclined circulation sections and means to secure them together.
30. In a fire-box, the combination of a 75 grate; a wall comprising a series of superposed sections inclined from one end of the fire-box toward the other; filler means between outer portions of said sections; and filler means between inner portions of sections adjacent said grate.
- In testimony whereof, I have signed my name to this specification, in the presence of two subscribing witnesses.
- JAMES M. McCLELLAN.
- Witnesses:
- HENRY T. WILLIAMS,
ROBERT H. KAMMLER.

It is hereby certified that in Letters Patent No. 1,203,376, granted October 31, 1916, upon the application of James M. McClellan, of Everett, Massachusetts, for an improvement in "Boiler and Fire-Box Constructions," an error appears in the printed specification requiring correction as follows: Page 4, line 48, claim 8, strike out the word "comprising" and insert a comma and the words, *the combination of*; and that the said Letters Patent should be read with this correction therein that the same may conform to the record of the case in the Patent Office.

Signed and sealed this 24th day of April, A. D., 1917.

[SEAL.]

F. W. H. CLAY,

Acting Commissioner of Patents.

Cl. 122—94.
